UNITED STATES PATENT OFFICE.

FRED E. BRIGHT, OF PHILADELPHIA, PENNSYLVANIA.

GRINDING-MACHINE.

1,198,614.

Specification of Letters Patent. Patented Sept. 19, 1916.

Application filed May 6, 1915. Serial No. 26,275.

To all whom it may concern:

Be it known that I, FRED E. BRIGHT, a citizen of the United States, residing at Philadelphia, in the county of Philadelphia and State of Pennsylvania, have invented 5 certain new and useful Improvements in Grinding-Machines, of which the following is a specification, reference being had therein to the accompanying drawing.

10 This invention relates to grinding or finishing machines, and has reference more particularly to that type of machine in which the work is rotated while being subjected to the action of an operating tool.

15 The invention is designed with special reference to the handling of annular forms or shapes, such for instance as the casing-members or bearing-rings of antifriction bearings, the particular form of mechanism

20 here shown as embodying my invention, being adaptable for operating on the bores of the inner casing-members of the bearings, in order to give the bore its proper and accurate finished condition.

25 In its general organization, the mechanism embodying my invention comprises a holder for the work, in this instance the inner casing-member of an antifriction bearing, which holder is adapted to be rotated so as to correspondingly rotate the work about its longitudinal axis, and which

30 holder is adapted also to be moved in a direction axially of the work in order to present all portions of the bore to the action 35 of the operating tool; a rotary tool-carrying member arranged within the work holder; and means for moving the tool-carrying member radially of the work holder to cause the tool to be fed to and enter more 40 deeply into the material of the work.

In the more specific embodiment of the 45 invention, the work holder is in the form of a rotatable sleeve movable axially of its axis of rotation, and the operating tool is in the form of a grinding wheel carried by a spindle extending longitudinally within the rotary sleeve and mounted for rotation eccentrically within an adjusting sleeve, which latter is mounted for rotary 50 oscillation within the rotary work holding sleeve, whereby the tool spindle may be adjusted radially of the rotary work-holding sleeve. These parts are arranged in an upright position, and the work-holding sleeve 55 is provided with an internal annular cham-

ber surrounding the tool spindle and in position to receive the grindings, water, and fine particles produced by the operation of the grinding wheel on the work. As a result of this construction, and arrangement, 60 the rotary parts are effectively balanced, and so sustained as to avoid undue wear and consequent misalignment; the work operated on is supported and exposed in the most convenient position for attachment, removal and examination; and the grindings, due to the operation of the grinding wheel on the work will leave the same promptly, and be collected and discharged from the machine, without danger 70 of their finding access to or interfering with the relatively movable parts.

The mechanism shown in the accompanying drawings illustrates one form of my invention by way of example and which 75 in practice has been found to answer to a satisfactory degree the ends to be attained. It will be manifest, however, that the construction may be modified and changed by the skilled mechanic without departing 80 from the limits of the invention; and further it will be understood that the invention is not limited to any particular form of construction of the parts except in so far as such limitations are specified in the 85 claims.

In the accompanying drawings: Figure 1 is a side elevation partly in section of my improved machine, the work operated on being shown in dotted lines. Fig. 2 is 90 a horizontal sectional plan view on the line *a—a* of Fig. 1. Fig. 3 is an end elevation of the machine as viewed in the direction of the arrow in Fig. 1. Fig. 4 is a view on an enlarged scale looking downward on 95 the work carrying sleeve, grinding wheel and adjacent parts. Fig. 5 is a horizontal sectional plan view on the line *b—b* of Fig. 1. Fig. 6 is a horizontal sectional view on the line *c—c* of Fig. 1. 100

Referring to the drawings: The operative parts of the machine are mounted on and sustained by a suitable frame 1 comprising a horizontal bed plate 2 supported by legs 3, from one side of which plate extends a standard 3'. At one end the bed plate is formed with a vertical circular opening 4 in which is firmly clamped the lower end of a vertical supporting sleeve 5 which extends upwardly some distance above the base 110

plate. The supporting sleeve is formed with a longitudinally extending circular opening disposed eccentrically of the axis of the sleeve, and in this opening is mounted for 5 rotary oscillation, an adjusting sleeve 6, the upper end of which is provided with an annular shoulder 6^a which rests on the upper end of the supporting sleeve, whereby the adjusting sleeve is sustained by the supporting sleeve. The adjusting sleeve is provided with a circular longitudinal opening which is disposed in eccentric relation to the axis of the sleeve, and in this opening is mounted for rotation, a tool-carrying spindle 10 7 extending at its upper end beyond the end of the adjusting sleeve 6, where the spindle has fixed to it an operating tool in the form of a grinding wheel 8. Near its upper end the spindle has fixed to it a cylindrical bearing collar 9 which is mounted for rotation in a bearing opening in the upper end of the adjusting sleeve, while near its lower end the spindle receives its rotary support from a ball bearing 10 supported at the lower end 15 20 25 30 35 40 45 50 55 60 65 of the adjusting sleeve, it being understood that the axes of the two end bearings for the spindle are coincident, but disposed eccentrically with relation to the central axis of the adjusting sleeve. As a result of this construction and relation of the parts, when the adjusting sleeve is oscillated within the supporting sleeve 5, the tool spindle will be shifted or adjusted radially, the purpose of this adjustment being to cause the grinding wheel to feed up to the work and enter more deeply into the material thereof. Surrounding the upper portion of the sleeves 5 and 6 and the inclosed tool spindle, is a work-carrying sleeve 11 which is adapted to be rotated so as to impart a corresponding rotation to the work, and which is adapted also to be moved axially so as to impart a corresponding feeding movement to the work in order to present all portions of the same to the action of the grinding wheel. The sleeve 11 is provided with an internal cylindrical neck 12 extending respectively above and below the lower end of the sleeve and connected thereto by means of a radially extending portion 13, which neck fits around the supporting sleeve 5 and has a bearing thereon in such manner that it may be moved axially thereof relatively to said bearing and also may be rotated thereon. The upper portion of the neck is spaced from the inner surface of the sleeve so as to form an annular chamber 14 which is open at its upper end, and which is closed at its lower end by means of the radially extending trough 16, the purpose of this chamber being to receive the grindings produced in the action of the wheel 8 on the work. The work, in the present instance the inner casting X of an antifriction bearing, is supported by means of a chuck Y or other suit-

able work holder applied to the upper end of the sleeve 11, and the latter being rotated and moved axially in the manner to be presently described, all portions of the bore of the work will be presented to the action of the grinding tool, which latter being rotated and shifted radially, will subject the bore to a grinding operation and give to the same its proper and accurate finished condition. In such operation it is usual to employ water to prevent the generation of excessive heat, and as the grinding operation proceeds, the water and grindings will flow downwardly by gravity and enter the chamber 14, from which they will be discharged through outwardly and downwardly extending pipes 15 leading outwardly through the side of the sleeve 11 from the bottom of the chamber, the discharge of the grindings being effected by the centrifugal force due to the rotation of the sleeve. The grindings are received in an annular trough 16 surrounding the lower end of the sleeve and supported in the manner to be more fully described hereinafter, from which trough they are discharged through an opening 16^a in the bottom of the same.

The grindings are prevented from reaching the bearings and relatively movable parts of the mechanism, by means of two annular shields 17 and 18, which surround and inclose the upper portions of the spindle and the supporting and adjusting sleeves. The shield 17 is fixed to the upper end of the supporting sleeve 5, and is provided with a downwardly extending neck 17^a projecting into the upper end of the chamber 14, and surrounding the upper portion of the neck 12. This shield is provided also with an upwardly extending neck 17^b projecting inwardly across the upper end of the adjusting sleeve 6 and being provided with an opening 17^c surrounding the tool carrying spindle 7, the opening being of such diameter as to admit of the radial adjusting movements of said spindle. The shield 18 is firmly fixed to the tool carrying spindle above the neck 17^b of the other shield, and is extended outwardly so as to cover the opening 17^c in said shield. The action of the shield 18 is to direct the grindings onto the shield 17, and the action of the latter is to direct the grindings downwardly into the chamber 14, these two shields thus coöperating in preventing the grindings from finding access to the relatively moving parts of the machine.

Rotary motion is imparted to the work-carrying sleeve 11 by means of a horizontal driving pulley 20 receiving vertical and radial support by means of an antifriction bearing 21, respectively from the bed plate 2 and the supporting sleeve 5, this pulley being driven by a belt 21^a receiving motion from any suitable source of power. The

pulley is formed with an upwardly projecting cylindrical extension 22, surrounding the downwardly extending portion of the neck 12, which latter is provided with keys 5 23 sliding loosely in vertical key ways 24 formed in the interior of the extension 22. As a result of this arrangement, the work carrying sleeve 11 may be moved up and down relatively to the driving pulley 20, 10 and in such movement the rotary motion of the pulley will be transmitted to the sleeve, whereby the latter is given an axial motion, and a rotary motion about its axis of movement.

15 The sleeve is given its axial movement by means of a vertically reciprocating member in the form of a horizontal lever 24 pivoted near one end by means of a horizontal pivot bolt 25, to the standard 3, and having its 20 opposite end forked so as to extend on opposite sides of the cylindrical extension 22 of the pulley. The forks of this lever are provided with supporting rollers 26 which bear beneath and give support to an inwardly 25 extending flange 16^b on the annular trough 16 before alluded to. This trough in turn gives support to the work carrying sleeve 11, through the medium of a thrust bearing 27, the result of this construction being 30 that while the trough and supported sleeve 11 will be moved up and down by the pivotal lever 24, the rotation of the sleeve will not be imparted to the trough. The lever 24 is moved up and down on its axis by means of 35 a cam 28 mounted on one end of a horizontal transverse shaft 29 mounted in suitable bearings in the standard 3', the said cam engaging a roller 30 journaled on the lever. The shaft 29 has fixed to it a worm wheel 40 31 driven by a vertical worm 32 mounted on a shaft 33 journaled in vertical bearings in the standard, the lower end of the shaft being extended below the bed plate and being provided with driving pulleys 34 45 which latter are driven by a belt 35 receiving motion from any suitable source of power.

The radial movement of the wheel spindle, to effect a corresponding movement of the 50 grinding wheel to cause the latter to feed up to and enter more deeply into the material of the work, is effected by means of a horizontal segment gear 36 fixed to the lower end of the adjusting sleeve 6 and engaged by a horizontal worm 37 mounted in bearings in the base of the frame, said worm being extended at the front of the frame where it is provided with a hand crank 38 55 for turning it. The worm has fixed to it adjacent the hand crank, a graduated wheel 39 adapted to be read in connection with a pointer 40 fixed to the frame, whereby the grinding wheel may be adjusted gradually and to predetermined distances.

60 65 The tool spindle receives its rotary mo-

tion from a driving pulley 41 fixed to its lower end and driven by a belt 42 receiving motion from a suitable source of power.

In the operation of the device the work being firmly held by the work holder on the upper end of the sleeve 11, the latter is rotated and moved back and forth axially by the mechanism described. The grinding wheel being rotated, and being fed radially by means of the hand crank 38, the wheel 70 will be caused to act on the interior of the bore of the work, and all portions of the latter will be presented by the rotary and axial movements of the work carrying sleeve, to the wheel, resulting in the grinding and 75 final accurate shaping of the bore. Due to the upright position of the parts, the grindings will quickly leave the wheel and work, and pass by gravity into the chamber 14 from which they will be discharged by 80 centrifugal force through the pipes 15, and will be received in the trough 16 and will leave the same from the bottom discharge opening therein. The upright position of the parts is of further advantage in that they 85 will be effectively balanced in their rotation, and will be subjected to a minimum of wear, and as such wear as results, will not affect the sides of the parts, the alinement of the tool spindle and work carrying sleeve will 90 not be disturbed.

Having thus described my invention, what I claim is:

1. In a machine of the type described, the combination of a rotary work sleeve adapted to carry a work holder, a rotary tool spindle extending permanently within the sleeve and adapted to carry an operating tool, and means for effecting a feeding movement of the work sleeve axially relatively to the tool 100 spindle.

2. In a machine of the type described, the combination of a rotary work-carrying sleeve, a rotary tool spindle extending within the said sleeve, means for effecting a feeding movement of the sleeve axially of the spindle, and means for effecting a feeding movement of the spindle radially of the sleeve.

3. In a machine of the type described, the combination of a work-carrying member and a tool carrying member extending one longitudinally within the other, and means for actuating the same to operate on the work, said members being formed and disposed relatively to leave an annular space 115 between them to receive the grindings.

4. In a machine of the type described, the combination of a rotary work-carrying member, and a rotary tool-carrying member, 120 said members being arranged in an upright position one within the other, and means for actuating the same to operate on the work, said members being formed and disposed relatively to leave an annular space be- 125 130

tween them into which the grindings may pass by gravity.

5. In a machine of the type described, the combination of a rotary work-carrying sleeve, a rotary tool-carrying spindle extending longitudinally within the sleeve, said parts being formed and disposed relatively to leave an annular space between them in position to receive the grindings, 10 and means for actuating said sleeve and spindle to operate on the work.

6. In a machine of the type described, the combination of a work-carrying member and a tool-carrying member extending one 15 longitudinally within the other, means for actuating the same to operate on the work, said members being formed and disposed relatively to leave an annular space between them to receive the grindings, and a shield 20 in position to direct the grindings into said space.

7. In a machine of the type described, the combination of a rotary work-carrying sleeve, a rotary tool-carrying spindle extending longitudinally within the same, said parts being arranged in an upright position and being formed and disposed relatively to leave an annular space between them to receive the grindings, and a shield carried 30 by the tool carrying spindle and serving to direct the grindings into said space.

8. In a machine of the type described, the combination of a rotary work-carrying sleeve, a supporting sleeve extending longitudinally within the same, a rotary tool spindle extending longitudinally within the supporting sleeve, said sleeves being relatively formed and disposed to leave an annular space to receive the grindings, a shield 35 carried by the supporting sleeve in position to direct the grindings into said space, and a shield carried by the tool spindle in position to direct the grindings onto the other sleeve.

45 9. In a machine of the type described, the combination of a rotary work-carrying sleeve, a supporting sleeve extending within the same with an annular space surrounding the supporting sleeve, and an annular shield carried by the supporting sleeve and extending into said space to direct the grindings into the same.

10. In a machine of the type described, the combination of a rotary work-carrying sleeve, a supporting sleeve extending within the same, a rotary tool spindle within the supporting sleeve, means for moving the tool spindle radially within the supporting sleeve, said work-carrying sleeve being 55 formed and disposed relatively to leave a space surrounding the supporting sleeve to receive the grindings, a shield carried by the supporting sleeve and having an opening therethrough to permit the radial movement 60 of the tool spindle, and a shield carried by

the tool spindle and extending over the opening in the first mentioned sleeve.

11. In a machine of the type described, the combination of a work-carrying sleeve, a tool-carrying spindle extending within the 70 sleeve, said sleeve being provided with an annular internal chamber surrounding the tool spindle and in position to receive the grindings, and means for actuating said parts to operate on the work. 75

12. In a machine of the type described, the combination of a work-carrying sleeve, a tool spindle extending within the sleeve, said sleeve being provided with an annular internal chamber surrounding the tool spindle and in position to receive the grindings, 80 and said chamber being provided with an opening for the discharge of the grindings, an annular trough in position to receive the grindings discharged from the chamber, 85 and means for actuating the sleeve and spindle to operate on the work.

13. In a machine of the type described, the combination of a work-carrying sleeve provided with a neck extending within the 90 same and spaced therefrom to form an annular chamber to receive the grindings, a rotary tool spindle extending within said neck, and means for actuating the said parts to operate on the work. 95

14. In a machine of the type described, the combination of a work-carrying sleeve, a tool spindle extending within the same, said sleeve being provided with an annular internal chamber surrounding the tool spindle and in position to receive the grindings, 100 and said chamber being provided with discharge openings extending outwardly through the sleeve; whereby the contents of the chamber will be discharged by centrifugal force, and means for actuating the sleeve and spindle to operate on the work. 105

15. In a machine of the type described, the combination of a work-carrying sleeve, a tool spindle extending within the same, 110 said parts being arranged in an upright position and said sleeve being movable vertically, a vertically reciprocating member supporting said sleeve, and means for reciprocating said member. 115

16. In a machine of the type described, the combination of a vertical rotary work-carrying sleeve movable axially, a rotary tool spindle therein, a horizontal driving pulley to which the sleeve is splined, means 120 for rotating the pulley, a vertically reciprocating member supporting the sleeve, and means for reciprocating said member.

17. In a machine of the type described, the combination of an axially movable 125 work-carrying member adapted to support the work in position to be operated on, a rotary driving member with which said work-carrying member has a sliding driving engagement, means for rotating the 130

driving member, and means for moving the work-carrying member axially; whereby the latter will receive rotary motion from the driving member.

5 18. In a machine of the type described, the combination of a rotary sleeve adapted to carry a work-holding device, a rotary tool-carrying spindle extending within the sleeve, and means for effecting a feeding 10 movement of the tool-spindle transversely of the axis of the sleeve.

15 19. In a machine of the type described, the combination of a rotary sleeve adapted to carry a work-holder, a rotary tool-spindle 15 extending within the sleeve and adapted to carry an operating tool, one of said parts being movable axially relatively to the other to cause the tool to traverse the work axially, and one of said parts being adjust-

20 able transversely relatively to the other to cause the tool to enter into the material of the work.

25 20. In a machine of the type described, the combination of a frame, a rotary sleeve mounted therein and adapted to carry a work-holding device, an oscillating adjusting sleeve within the rotary sleeve, and a rotary tool-spindle mounted eccentrically within the adjusting sleeve; whereby by the oscillation of the adjusting sleeve, the spindle 30 will be moved transversely of the rotary sleeve.

35 21. In a machine of the type described, the combination of a frame, a rotary sleeve mounted therein and adapted to carry a work-holding device, a supporting sleeve

within the rotary sleeve, an adjusting sleeve mounted eccentrically within the supporting sleeve for oscillation therein, and a rotary tool-carrying spindle mounted eccentrically within the adjusting sleeve. 40

22. In a grinding machine, and in combination with a frame sustaining a bearing surface, a work-carrying member rotatable on said bearing surface, a rotary tool-spindle 45 adapted to carry an operating tool, means for reciprocating the work-carrying member in the direction of its axis of rotation and relatively to said bearing surface to cause the work to traverse the tool, and 50 means for effecting a feeding motion of the work-carrying member and tool-spindle one relatively to the other transversely of said axis to cause the tool to enter the material of the work. 55

23. In a grinding machine and in combination with a frame sustaining a cylindrical bearing surface, a work-carrying sleeve surrounding said bearing surface and rotatable thereon, a rotary tool-spindle, 60 means for reciprocating the work-carrying sleeve on its cylindrical bearing surface in the direction of the axis of rotation of the sleeve, and in relation to said bearing surface to cause the work to traverse the tool, and 65 means for imparting a feeding movement to the tool-spindle transversely of said axis of rotation to cause the tool to enter the material of the work.

In testimony whereof, I have affixed my 70 signature in presence of two witnesses.

FRED E. BRIGHT.
